UNITED STATES PATENT OFFICE.

GEORGE G. FLOYD, OF CHICAGO, ILLINOIS, ASSIGNOR TO AMERICAN STEEL FOUNDRIES, OF CHICAGO, ILLINOIS, A CORPORATION OF NEW JERSEY.

METHOD OF MAKING CAR TRUCKS.

Application filed January 30, 1922. Serial No. 532,576.

To all whom it may concern:

Be it known that I, GEORGE G. FLOYD, a citizen of the United States, residing at Chicago, in the county of Cook and State 5 of Illinois, have invented certain new and useful Improvements in a Method of Making Car Trucks, of which the following is a specification.

This invention relates to methods of making car trucks.

In the manufacture of railway car trucks, the various parts thereof are built in large numbers and assembled as the parts are picked promiscuously from the different 15 stock piles. Most of the parts, including the side frames, are castings. Such side frame castings are provided with journal box openings which presumably are of a given dimension from center to center. In 20 practice, however, it has been found that at times there is a variance from this dimension. Let it be assumed that the distance between such centers is one-eighth of an inch greater on one side frame than on the one 25 on the opposite side of the truck. Under such conditions the truck wheels rolling along a straight track would move to the right or left one-eighth of an inch for a truck distance equal to the cross distance from 30 the center of the thread of one wheel to the center of the thread of the opposite wheel on the same axle. The distance from the center of one rail to the center of the opposite rail happens to be about one-half of the circumference of a thirty-three (33) inch 35 wheel. Therefore if the axle is one-eighth of an inch out of square with the track it would roll to the right or left one-quarter of an inch in one revolution of a thirty-three 40 inch wheel, and it would roll on indefinitely one-quarter of an inch out of line for every revolution of the wheel if the wheel flanges did not bear against the inside of the rail. As the flanges come in contact with the rail 45 there is, of course, the same tendency for the wheel to roll to the right or left, and the work, therefore, of keeping the wheel rolling in a straight line is taken up by the friction between the flanges of the wheels 50 and the inside of the rail. This friction, which can be calculated in inch pounds or foot pounds per mile of track, is astonishingly high.

Accordingly, one of the objects of this invention is to overcome such flange and rail

wear and to provide a simple type of railway car truck in which the relation between the various parts thereof can be accurately determined and controlled and as a result thereof maintain the wheel axles in parallelism.

Another object is to provide a simple and accurate method for determining the location of relatively associated truck parts and assembling same.

These and other objects are accomplished by means of the invention disclosed on the accompanying sheets of drawings, in which—

Figure 1 is a fragmentary side elevation 70 of a railway car truck embodying my invention;

Figure 2 is a fragmentary top plan view of the same;

Figure 3 is a fragmentary side elevation 75 of the same railway car truck with certain of the parts removed;

Figures 4, 5 and 6 are sectional views taken in the plane of lines 4—4, 5—5 and 6—6 of Figure 3;

Figure 7 is a detail side elevation of one of the equalizing levers; and

Figure 8 is a side elevation of the associated equalizing lever.

The various novel features of the invention will be apparent from the following description and drawings and will be particularly pointed out in the appended claims.

Referring to the figures of the drawings, it will be noted that my invention is illustrated in connection with a six-wheel railway car truck in which the parts are duplicated on each side of the truck. Each side includes a side frame 10 having end journal box jaws 11 forming openings 12 for the reception of end journal boxes 13. The frame is also provided with openings 14 for the reception of the ends of transverse bolster members 15. Equalizing levers 16 and 17 transmit the loads from the bolster members to an intermediate journal box 18, nests of springs 19 preferably being interposed between the ends of the bolster members 15 and the equalizing levers 16 and 17.

As pointed out above, this invention relates primarily to a method of and means for locating the relative positions of various parts of the truck so that all of the axles originally will be placed in parallel and will be maintained in parallel relationship. To 110

this end, the end journal box jaws 11 are accurately machined so that the distance A between the centers of the end journal boxes will be a definite predetermined dimension. 5 The pivot holes 20 and 21 are then drilled through the side frame a definite predetermined distance B inwardly from the vertical center lines of the journal box openings 12. It will be noted that one equalizing lever on each side of the truck is provided with jaws 22 for the reception of an intermediate journal box 18. These jaws are accurately machined to rigidly receive the intermediate journal boxes. After these 10 jaws 22 are finished the pivot holes 23 are drilled through one end of the equalizing lever 16 a definite predetermined distance C from the center line of the intermediate journal box opening, whereupon each of 15 said equalizing levers may be pivotally connected to the side frame by a pin 24. The other equalizing lever 17 will then be jig drilled as were the other equalizing levers, but a variation in the length of the equalizing lever 17 will make very little difference 20 because if the side frame is machined so that the dimension A is exact and the dimension B from the center of these jaws to the pins 24 is drilled an exact amount 25 and the jaw equalizer 16 is properly jig drilled, the short wheel base D accordingly will be exactly the same dimension on both sides of the truck. While there may be a slight difference between the short wheel 30 base D and the wheel base E on the same side of the truck, there will be exactly this same difference on the opposite side of the truck.

Therefore the three wheel axles 25, 26 40 and 27, at all times will be parallel. The equalizing levers 17 are pivotally connected to the side frame by pivot pins 28 similar to the pivot pins 24. It will be understood that the inner end of the equalizing lever 45 17 will rest upon and be telescopically arranged with the inner end of the associated equalizing lever 16.

It is my intention to cover all modifications of the invention falling within the 50 spirit and scope of the following claims.

I claim:

1. The method of making a six-wheel railway car truck including a side frame having two pairs of end journal box jaws, 55 and two equalizing levers pivoted to said

side frames on each side of said truck, one equalizing lever on each side having a pair of journal box jaws for an intermediate journal box, which method consists in first machining the end journal box jaws to a definite dimension from center to center, then drilling the equalizing lever pivot holes in said side frames a definite distance inwardly from the center lines of said end journal box jaws, then machining the equalizing lever jaws, and then drilling the pivot holes of said jaw equalizing levers an exact distance from the center line of the intermediate equalizing journal box jaws whereby all of the wheel axles will be parallel. 60 65 70

2. The method of making a six-wheel railway car truck including a side frame having two pairs of end journal box jaws, and two equalizing levers pivoted to said side frames on each side of said truck, one equalizing lever on each side having a pair of journal box jaws for an intermediate journal box, which method consists in first finishing the end journal box jaws to a definite dimension from center to center, then providing the equalizing lever pivotal centers in said side frames a definite distance inwardly from the center lines of said end journal box jaws, then finishing the equalizing lever jaws, and then providing the jawed equalizing levers with pivot means an exact distance from the center line of the intermediate journal box jaws whereby all of the wheel axles will be parallel. 75 80 85

3. The method of making a six-wheel railway car truck including a side frame having two pairs of end journal box jaws and two equalizing levers pivoted to said side frame on each side of said truck, which method consists in first finishing the end journal box jaws to a definite dimension from center to center, then providing the equalizing lever pivot means in said side frames a definite distance inwardly from the center lines of said end journal box jaws, then machining equalizing lever portions for receiving the intermediate journal box, and then providing said equalizing levers with pivot means to cooperate with the pivot means of said side frames whereby all of the wheel axles will be parallel. 90 95 100 105

Signed at Chicago, Illinois, this 24th day of January, 1922.

GEORGE G. FLOYD.
